H. A. DOUGLAS.

ELECTRICAL CONNECTOR,

APPLICATION FILED NOV. 21, 1917.

1,325,007.

Patented Dec. 16, 1919.

Inventor:
Harry A. Douglas.
By G. L. Clegg Atg.

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

ELECTRICAL CONNECTOR.

1,325,007.

Specification of Letters Patent. Patented Dec. 16, 1919.

Application filed November 21, 1917. Serial No. 203,098.

To all whom it may concern:

Be it known that I, HARRY A. DOUGLAS, citizen of the United States, residing at Bronson, in the county of Branch and State 5 of Michigan, have invented a certain new and useful Improvement in Electrical Connectors, of which the following is a full, clear, concise, and exact description.

My invention relates to electrical connectors employed for establishing circuits or acting as links that connect circuit sections. These connectors include cylindrical shells and contact carriers assembled therewith.

It is one object of my invention to provide 15 an improved means for assembling such shells and carriers made of insulation formed in single pieces or in sections, the means which I preferably employ being of particular service in maintaining two sections of a split carrier in assembly while at the same time preventing rotary movement of the carrier sections with respect to each other and the shell and longitudinal movement of the carrier sections with respect to 25 each other and the shell. I accomplish the objects of my invention by effecting locking interengagement of the carrier directly with the shell. Where the carrier is formed in sections, the longitudinal movement and 30 rotative movement of the sections with respect to each other and with respect to the shell are prevented by such locking interengagement.

I will explain my invention more fully 35 by reference to the accompanying drawing showing the preferred embodiment thereof and in which Figure 1 is a view in longitudinal section, with end contact carriers shown in elevation, of a connector made in 40 accordance with one embodiment of the invention; Fig. 1^a shows a single piece carrier, otherwise similar to the carrier of Fig. 2; Fig. 2 is a sectional view on line 2—2 of Fig. 1; Fig. 3 is a side elevation of the connector minus the end contact carriers; Fig. 4 is a view in side elevation of the structure; Fig. 5 is a longitudinal sectional view illustrating a modified form of contact carrier at the intermediate portion of the shell, the end contact carriers being removed; Fig. 6 shows the shell and contact carrier sections in readiness to be assembled, the sections of the contact carrier being here shown in separated relation.

55 Like parts are indicated by similar char-

acters of reference throughout the different figures.

The connector shown includes a cylindrical metallic shell 1 having bayonet slots 2 and 3 at its opposite ends in which may be received the bayonet pins 4 and 5 provided upon the contact carriers 6 and 7. The contact carrier 6 is in the nature of a connecting plug and the contact carrier 7 is in the nature of the base of an incandescent lamp 8. 65 When the invention is embodied in a "single" pole construction (to which the invention is not to be limited) the circuit is partially established by way of the metallic shell 1 and the metallic sheath that surrounds the base of the lamp and which sheath is in electrical contact with the shell. One terminal of the lamp filament is connected with the sheath of the lamp base and the other terminal of the lamp filament is 70 connected with the central contact 9. The contact plug 6 has a central contact 10. In the construction shown in Fig. 1 there is provided a contacting metallic spring barrel 11 that is in engagement with the contact 10 75 and a contact 12 that is in engagement with the contact 9, this contact 12 projecting from the end of the contact barrel 11 that is adjacent the lamp and being forced into engagement with the lamp contact 9 by means 80 of the coiled spring 13 housed within the spring barrel 11. In the form of the invention shown in Fig. 5 there is provided the contact 14, a coiled spring 15 intervening between the contacts 12 and 14 to press 85 them apart and respectively into engagement with the central contacts upon the plug and lamp base.

The contact carrier at the intermediate portion of the shell, in the construction 90 shown in Figs. 1 and 2, is formed in two disks 16, 17 of suitable insulating material which have centrally alined holes through which the spring barrel 11 projects and in which such spring barrel may move longitudinally of the connector. The invention, however, is not to be limited to the formation of the carrier in sections, as it may be formed in one piece as illustrated in Fig. 1^a. 100

In the form of the invention shown in 105 Fig. 5 the contact carrier sections 16, 17 are outwardly bulged at their central portions, the ends of the bulges being contracted to reduce the diameters of the ends of the opening in the carrier through which the con- 110

tacts 14 and 12 project. The spring 15 is disposed directly in this opening and exerts its pressure upon the heads of the contacts 12 and 14, these heads engaging the shoulders at the ends of the contact carrier that are formed by reducing the opening at the ends of the contact carrier whereby such spring 15 is prevented from ejecting the contacts from the carrier.

- 10 Each of the opposed circular portions of the contact carrier sections is formed with diametrically opposite key slots 18 in its periphery that extend longitudinally of the shell 1 and receive the diametrically opposite insetting inwardly depressed keys 19 integrally formed with an intermediate portion of the shell and each integrally connected therewith at its ends, these keys and key slots extending longitudinally of the shell whereby rotary movement of the carrier with respect to the shell is prevented. Each key 19 is supported by the wider shell portions 20 that constitute heads of said keys and the means by which the keys are held in place. Recesses 21 are formed in the mid-portions of the sides of the keys 19, these recesses forming shoulders 22 extending transversely of the shell. The space between each pair of opposite shoulders 22 corresponds to the thickness of the peripheral portion of the carrier or the aggregate thickness of the peripheral portions of the assembled sections of the carrier to prevent movement of the carrier or assembled carrier sections longitudinally of the shell. The shell is initially in the shape shown in Fig. 6. In assembling the carrier and shell, the carrier is moved into the zone of the recesses 21 whereafter the key portions 19, 20 of the shell are merely pressed inwardly to bring the keys 19 into the slots 18 of the carrier and to bring the shoulders 22 on the shell into abutting engagement with the portion of the carrier that is disposed between these shoulders. The shoulders 22 prevent longitudinal movement of the carrier and the keys 19 prevent rotary movement of the carrier sections with respect to each other and with respect to the shell.
- 45 The assembly of the shell and carrier is simply effected, no supplemental fastening devices being required and while the invention is of particular utility in holding carriers in place that are made in sections, it is not to be limited in its adaptation to carriers that are formed in sections. While the direct interengagement of the shell and carrier sections illustrated holds these carrier sections in facial contact with each other, I do not wish to be limited to such close assembly of the carrier sections.

While I have herein shown and particularly described the preferred embodiment

of my invention I do not wish to be limited to the precise details of construction shown as changes may readily be made without departing from the spirit of my invention, but having thus described my invention I claim as new and desire to secure by Letters Patent the following:—

1. A connector including a cylindrical shell; an inwardly depressed key integrally formed with an intermediate portion of the shell and integrally connected at its ends with the shell, said key having a notch formed in the mid-portion of a side to form shoulders extending transversely of the shell; and a contact carrier within the shell provided with a key slot in its periphery, which slot extends longitudinally of the shell, a portion of the carrier being received between said shoulders while the portion of the key between said shoulders is received in said key slot.

2. A connector including a cylindrical shell; an inwardly depressed key integrally formed with an intermediate portion of the shell, said key having a notch formed in the mid portion of a side to form shoulders extending transversely of the shell; and a contact carrier within the shell provided with a key slot in its periphery, which slot extends longitudinally of the shell, a portion of the carrier being received between said shoulders while the portion of the key between said shoulders is received in said key slot.

3. A connector including a cylindrical shell; a key integrally formed with an intermediate portion of the shell and integrally connected at its ends with the shell, said key having a notch formed in the mid-portion of a side to form shoulders extending transversely of the shell; and a contact carrier within the shell provided with a key slot in its periphery, which slot extends longitudinally of the shell, a portion of the carrier being received between said shoulders while the portion of the key between said shoulders is received in said key slot.

4. A connector including a cylindrical shell; a key integrally formed with an intermediate portion of the shell, said key having a notch formed in the mid-portion of a side to form shoulders extending transversely of the shell; and a contact carrier within the shell provided with a key slot in its periphery, which slot extends longitudinally of the shell, a portion of the carrier being received between said shoulders while the portion of the key between said shoulders is received in said key slot.

In witness whereof I hereunto subscribe my name this 10th day of November, A. D. 1917.

HARRY A. DOUGLAS.
